Primary Examiner—Louis S. Zarfas**[57] CLAIM**

The ornamental design for a safety umbrella, as shown and described.

DESCRIPTION

FIG. 1 is a perspective view of a safety umbrella showing my new design in a closed condition;

FIG. 2 is a side elevational view thereof, the side opposite being a mirror image of the side shown in FIG. 2;

FIG. 3 is a bottom plan view thereof;

FIG. 4 is a top plan view thereof;

FIG. 5 is a perspective view thereof in an open configuration;

FIG. 6 is a side elevational view thereof, the side opposite being a mirror image of the side shown in FIG. 6;

FIG. 7 is a bottom plan view thereof; and,

FIG. 8 is a top plan view thereof.

FIG. 1.

FIG. 5.

FIG. 2.

FIG. 6.

FIG. 3.

FIG. 7.

FIG. 4.

FIG. 8.
